FISHING LURE

Christopher F. Conder, Fairport, and William R. Elliott,
Poland, Ohio

Application September 21, 1954, Serial No. 32,383

Term of patent 14 years

(Cl. D31—4)

FIG. 1

FIG. 2

FIG. 3

To all whom it may concern:

Be it known that we, Christopher F. Conder and William R. Elliott, citizens of the United States of America, residing at Fairport, and Poland, Ohio, respectively, have invented a new, original, and ornamental Design for a Fishing Lure, of which the following is a specification, reference being had to the accompanying drawing, forming a part hereof.

Figure 1 is a top plan view of the fishing lure showing our new design.

Figure 2 is a rear end view;

Figure 3 is a side view.

The dominant feature of our design resides in the full line portion of the drawing.

We claim:

The ornamental design for a fishing lure, as shown and described.
